UNITED STATES PATENT OFFICE

105,840

DESIGN FOR A GASOLINE PUMP

Henry H. Campbell and Rex J. Myers, Cleveland,
Ohio, assignors to Ferro Machine & Foundry
Company, Cleveland, Ohio, a corporation

Application July 16, 1937, Serial No. 70,486

Term of patent 7 years

To all whom it may concern:

Be it known that we, Henry H. Campbell and Rex J. Myers, citizens of the United States, residing at Cleveland, in the county of Cuyahoga and State of Ohio, have invented a new, original, and ornamental Design for a Gasoline Pump, of which the following is a specification, reference being had to the accompanying drawings, forming a part thereof, in which

Figure 1 is a perspective view of our new design for a gasoline pump, showing the front and one side thereof.

Figure 2 is a front view of the design shown in Figure 1.

Figure 3 is a perspective view of our new design for gasoline pump, taken in a direction opposite to that of Figure 1 and illustrating especially the rear portion and other side thereof.

Figure 4 is a top view of our design for gasoline pump.

We claim:

The ornamental design for a gasoline pump, substantially as shown.

HENRY H. CAMPBELL.
REX J. MYERS.
